CLAIM

The ornamental design of a drinking glass, as shown and described.

DESCRIPTION

FIG. 1 is a perspective view of a drinking glass showing my new design;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof;

FIG. 5 is a bottom plan view thereof; and,

FIG. 6 is a sectional view thereof.

*Fig. 4**Fig. 1**Fig. 2**Fig. 3**Fig. 5**Fig. 6*
